Primary Examiner — Richard E Chilcot*(74) Attorney, Agent, or Firm* — Birch, Stewart, Kolasch & Birch, LLP(57) **CLAIM**

The ornamental design for a door with a display screen, as shown and described.

DESCRIPTION

1. Door with a display screen

1.1 : Perspective

1.2 : Front

1.3 : Back

1.4 : Left

1.5 : Right

1.6 : Top

1.7 : Bottom

1.8 : Perspective view showing the door in a state of use
The diagonal shading lines in the reproductions are used to show the translucent material of the claimed design. The broken lines shown in Figure 1.8 depict portions of the door with a display screen that form no part of the claimed design.**1 Claim, 8 Drawing Sheets**(56)
